UNITED STATES PATENT OFFICE.

BYRDE CAMPBELL, OF EVANSVILLE, INDIANA.

DESIGN FOR A COAL-CABINET.

58,995.

Specification for Design.

Patented Sept. 13, 1921.

Application filed March 14, 1921. Serial No. 452,329. Term of patent 14 years.

To all whom it may concern:

Be it known that I, BYRDE CAMPBELL, a citizen of the United States, residing at Evansville, in the county of Vanderburg and State of Indiana, have invented a new, original, and ornamental Design for a Coal-Cabinet, of which the following is a specification, reference being had to the accompanying drawing, forming part thereof.

Figure 1 is a front elevation of a coal cabinet showing my new design, and Fig. 2 is a side elevation.

I claim:

The ornamental design for a coal cabinet as shown.

BYRDE CAMPBELL.
